(74) Attorney, Agent, or Firm — Troutman Sanders LLP;
Ryan A. Schneider; Chris N. Davis(57) **CLAIM**

The ornamental design for a dispensing device with refill cartridge, as shown and described.

DESCRIPTION

FIG. 1 is an isometric view of a dispensing device with refill cartridge of the present invention;

FIG. 2 is a front view of the dispensing device with refill cartridge of FIG. 1;

FIG. 3 is a back view of the dispensing device with refill cartridge of FIG. 1;

FIG. 4 is a side view of the dispensing device with refill cartridge of FIG. 1;

FIG. 5 is the other side view of the dispensing device with refill cartridge of FIG. 1;

FIG. 6 is a top view of the dispensing device with refill cartridge of FIG. 1; and,

FIG. 7 is a bottom view of the dispensing device with refill cartridge of FIG. 1.
